GARMENT SHIELD
Elizabeth M. Wonacott, 9301 Lenore Drive,
Garden Grove, Calif.
Filed Feb. 1, 1963, Ser. No. 255,570
10 Claims. (Cl. 2-53)

This invention pertains to a garment shield and more particularly to a garment shield which is adapted to be disposed of after it has been used once. This application 10 is a continuation-in-part of patent application Serial No. 172,155, filed Feb. 9, 1962, now abandoned, for "Disposable Garment Shield," by Elizabeth M. Wonacott.

There is an essential and a decided need to prevent human perspiration from damaging clothes.

Garment shields are frequently used to shield the sources of perspiration from the garment of the wearer. Previously known garment shields are sufficiently expensive that it is impractical to dispose of the garment shield after it has been used. It is usual to launder the garment shield so that it can be re-used. Laundering is not only inconvenient but also packs the shield reducing its absorbent qualities.

The garment shield of this invention is sufficiently inexpensive that it may be packaged in packages—for example of fifty or one hundred—to be used once and thrown away. It is not only more convenient and sanitary than the non-disposable shields but also more effective and more comfortable to wear.

Some attempts have been made in the prior art to create disposable garment shields. For example, Patent No. 2,005,232 to H. V. Marsh for a "Dress Shield" shows the use of flesh colored crepe or tissue paper as an absorbent material covered by cheese cloth or the like. A sheet of waxed paper is used as a moisture barrier. Such a 30 device would be rough and irritating to the wearer, the paper would become weak after it became wet, and the shield would rustle with the movement of the wearer.

Patent No. 1,897,952 to Du Pont for a "Garment Shield and Method of Making Same" also uses crepe 40 paper, a weak and irritating material.

Patent No. 2,654,888 to Brightman for a "Dress Shield" shows a garment shield which has a coarse outer surface of preferably coarse weave material such as Fiberglas and rayon. Such an outer material would irritate the body 45 of the wearer. Further, it is necessary in the Brightman device to provide holes in the outer wall to allow perspiration to pass into an inner filler. The filler is adapted to be disposed of but not the outer cover. The Brightman device in addition to being only semi-disposable would be substantially more expensive, less efficient and more 50 irritating to the body of the wearer than the device of this invention.

The garment shield contemplated by this invention is a multilayer garment shield in which the outer layers are preferably nylon gauze. Nylon gauze has the feature that it is very strong, non-irritating because of lack of abrasive qualities, and very porous. The preferred nylon gauze has a bias thread so that when two layers are overlapped with their bias directions opposite, a very strong pair of layers results. Alternatively two oppositely directed bias threads can be used in the same layer.

The device of this invention uses cellulose material such as cotton as a perspiration absorbing member. The cotton layer is positioned beneath, preferably, a double layer of nylon gauze.

A moisture barrier of very thin polyethylene or polyvinyl plastic—but preferably polyethylene—is used to prevent perspiration from reaching the clothes. The plastic is made as thin as mechanically practical which

2

allows it to present a moisture barrier without having a characteristic which causes it to rustle when the wearer moves.

The side of the garment shield which is adapted to contact the garment also is preferably covered by a double layer of nylon gauze with the bias threads in opposite directions. Alternatively one layer with two oppositely directed bias threads can be used.

In its preferred shape the blank from which the dress shield is made is substantially oval in shape. The oval members are laid on top of each other in the sequence nylon gauze, nylon gauze, polyethylene or polyvinyl plastic, cellulose material, nylon gauze, nylon gauze. The cross fibre of the nylon gauze is preferably aligned parallel to the minor axis of the oval with the bias threads displayed at an angle relative to the direction of the major axis of the oval.

To fasten the multilayers of the garment shield together, it is desirable to apply heat and pressure to the periphery of the stack of blanks. This may be done in a plurality of points or about the entire periphery of the blanks.

In order better to fit the body contour of the wearer, the oval stack of blanks is folded about the minor axis of the oval stack. To contour the stack of blanks to fit the curvature of the arm, a substantially crescent shaped indentation is made in the folded portion to depress the fold in its central region. The crescent shaped indentation should extend for substantially two-thirds of the central portion of the fold. The indentation, then, amounts to a fold in the opposite direction, along the minor axis of the oval extending from the major axis on either side thereof for approximately two-thirds of the distance from the center of the oval to the periphery of the blank. On either side of the indented fold are a pair of crescent shaped folds positioned to accommodate the indented fold.

When a garment is worn, the side seam of the garment is usually not directly under the arm. When a garment shield is worn, usually approximately two-thirds of it should be forward of the seam. In accordance with this invention, appropriate positioning marks are provided on the outer surface of the garment shield so that the shield may be aligned with the seam of the garment before the garment is put on.

It is also desirable in accordance with this invention to provide a plurality of adhesive surfaces on the periphery of the surface of the shield which goes next to the garment. It would be apparent that the presence of the adhesive surfaces is optional for some kinds of material—for example cashmere sweaters—will not tolerate the use of adhesive surfaces.

It is therefore an object of this invention to provide a disposable garment shield.

It is more particular object of this invention to provide a disposable garment shield which is very inexpensive relative to pre-existing shields.

It is another specific object of this invention to provide a disposable garment shield which is extremely strong.

It is still another specific object of this invention to provide a disposable garment shield which has a non-rustling moisture barrier.

It is still another specific object of this invention to provide a disposable garment shield which is easily fabricated to conform to the contour of the wearer.

It is also a specific object of this invention to provide position marks on the exterior surface of a disposable garment shield.

It is still another object of this invention to provide a method for making a disposable garment shield.

Other objects will become apparent from the following

description together with the accompanying drawings in which:

FIG. 1 is a partially broken plan view of a typical garment shield in accordance with this invention;

FIG. 2 is a profile view taken at 2-2 in FIG. 1;

FIG. 3 is an oblique view showing the layers of the multilayered garment shield of this invention;

FIG. 4 is a side view of the garment shield of this invention in its folded position;

FIG. 5 is a view, partially in section, taken at 5-5 in FIG. 4.

FIG. 1 shows the surface of the garment shield of this invention which is adapted to contact the body of the wearer. The garment shield 10 is preferably substantially oval in shape. The garment shield blank is folded approximately along the minor axis 12 of the oval. The fold 14 is away from the side of the garment shield which is adapted to contact the body of the wearer. The fold 14 is intended at 20 substantially symmetrically about the major axis 16 for a distance of approximately two-thirds of the way from the major axis 16 to the outer periphery 18 of the shield.

The indented portion 20 of fold 14 is substantially crescent shaped and is adapted to depress the central portion of fold 14 to contour the garment shield to the body of the wearer. The center of the indentation 20 has a fold 22. The leaves 24 and 26 on either side of the fold 22 extends from the fold 22 toward the surface 28 of the garment shield. Two additional folds are needed at 30 and 32 to form the demarcation line between the surface 28 and the indentation 20.

A plurality of position marks, four of which are shown at 34, 36, 38 and 40, are positioned on the outer surface 28 of the garment shield. The positioning marks may be on both outer surfaces but are preferably at least on the outer surface which is adapted to come into contact with the body of the wearer. The side seam on most garments is not centered on the side of the body of the wearer. Instead, it is usually positioned so that two-thirds of the body of the wearer is forward of the seam. Thus, for proper positioning of the garment shield two-thirds of the garment shield should be forward of the seam. The shown positioning marks 34, 36 are on a line substantially parallel to the major axis 16 of the oval garment shield 10. The line connecting lines 34 and 36 intersects the minor axis 12 of the garment shield 10 at a point substantially one-third of the distance across the minor axis 12 of the garment shield 10 from the major axis 16, as shown at 35 in FIG. 4. Similarly, a line connecting position marks 38 and 40 is substantially parallel to the major axis 16 and is positioned approximately one-third of the distance across the garment shield measured on the minor axis 12 as shown at 37 in FIG. 4.

It may sometimes be desirable to attach adhesive members to the periphery of the garment shield 10 on the surface which comes into contact with the clothes. The adhesive surface may extend entirely around the periphery of the shield or may be a plurality of individual adhesive segments. The segments need not be of the same size and shape. Adhesive segments are shown by way of example at 42, 44, 46, 48, 50 and 52. The use of the adhesive members is optional for some clothing will not tolerate such use.

An especially significant feature of this invention is the material selected for the multilayered garment shield and the sequence of layers thereof.

The outer layer 54 of material on the side of the shield adapted to come into contact with the body of the wearer is preferably of nylon gauze. The nylon gauze has one thread direction which is shown in the exemplary pattern in FIG. 1 at 66 substantially parallel to the minor axis 12 of the garment shield. A second thread 68 is interwoven with the threads 66 on a bias angle 70 relative to

5 a line 72 which is parallel to the major axis 16 of the garment shield. The nylon weave is very coarse and the interstices between the threads are preferably filled with a gauze material. The nylon gauze has the advantage that it is non-irritating to the body of the wearer. It is chemically inert to the perspiration and other body fluids of the wearer. It is not abrasive. It is very strong and does not ravel nor flake.

Although one layer of nylon gauze is sufficient to come within the spirit and the scope of this invention, it is preferable to underlay the outer layer 54 with a second layer 56 of nylon gauze substantially identical to the layer 54. The thread 72 of layer 56 is substantially parallel to the minor axis 12 of the garment shield, and the bias thread 74 forms a bias angle 76, with a line parallel to the major axis 16 of the garment shield, which is opposite in direction from the bias angle 70 of layer 54.

It is also within the spirit of this invention to use both bias threads 68 and 74 along with thread 66 in a single layer.

Under nylon gauze 56 is a layer 58 of absorbent material 58. It is preferable that layer 58 be fabricated of some material such as, for example, cotton. Paper is not satisfactory because it tends to crumble, pack and flake.

25 Under layer 58 is a layer 60 of a polyethylene or polyvinyl plastic material. The plastic material of layer 60 is preferably polyethylene. Layer 60 is preferably as thin as possible while still maintaining the desired mechanical strength. The thinness is desirable in order to prevent the garment shield from rustling when the wearer moves. It has been found that a thickness of approximately one one-thousandth of an inch is entirely satisfactory for the layer 60.

30 Layers 62 and 64 which are adapted to be positioned adjacent to the clothing of the wearer are fabricated of nylon gauze substantially identical to that in layers 54 and 56. Again it is desirable that two layers be used although one layer will fall within the spirit and scope of the present invention. When two layers are used it is preferable that the bias angle of the bias thread of layer 62 form an angle in an opposite direction from the bias angle of layer 64 relative to a line parallel to the major axis 16 of the garment shield. When one layer is used it is preferable to use two oppositely directed bias threads and a third thread direction similar to threads 68, 74 and 66.

When heat and pressure are applied around the periphery of the garment shield the material—particularly the polyethylene or polyvinyl plastic—fuses and fastens all of the layers together. Both heat and pressure are required to fuse the material and the amount of heat and pressure depends upon the relative thickness of the layers.

55 The indentation 20 and the fold 14 may be made by heat and pressure or by pressure alone. The indentation 20 and the fold 14 should not have sufficient heat applied to fuse the material for in the region where the material is fused it does not have the breathing and absorbing qualities which are desired in a garment shield.

60 To fabricate a garment shield, it is desirable to cut the layers in blanks of the proper shape. This shape, as explained above, is preferably an oval shape. The layers are laid in the described sequence upon a flat plate and are fused by the application of pressure and heat. The pressure and heat, for example, may be applied by a hand iron as shown at 80. The indentation 20 may, for example, be made by a heated pair of matching dies. It may also be made without heat by a pair of pressure dies which are contoured to the desired shape.

65 The fold 14 may be made by the application of heat and pressure or pressure alone. To make the fold 14, the garment shield is folded about its minor axis and heat or pressure or both is applied at fold 14.

Automatic machinery may be used to fabricate the garment shield described herein. For example, the material could be placed on a plurality of rollers and interleaved, by means well known in the art, to provide a con-

tinuous strip of multilayered material. The stacked blanks could then simultaneously be fused and cut. At the same time the periphery is fused and cut, the indentation 20 could be made. The entire cutting, fusing and indenting process could be carried out by means of a pair of matching dies. The matching dies could be stationary or could be movable with the flow of material. The individual garment shield members could then be extracted by a suction cup, or the like, which would be adapted to grasp the individual shields and fold them about their minor axis. The folds could then be pressed by a pair of pressure members and the folded or unfolded garment shield could then be packaged by known packaging techniques.

Thus, the garment shield of this invention presents a significant advance over the art in that it provides extreme convenience in a relatively inexpensive garment shield which has all the qualities of more expensive shields.

Further, the garment shield described in this invention has the decided advantage that it may be made by mass production techniques, packaged and sold as a disposable item.

The garment shield of this invention also has the unique feature of having positioning marks on the outer surface thereof which are adapted to aid the wearer in attaching the garment shield to the inner surface of the garment before the garment is worn.

The material selected for use in the garment shield of this invention has the advantage of being soft and very comfortable on the wearer.

The garment shield of this invention also has the desirable quality of being moisture proof without having a rustling characteristic when the wearer moves.

Thus, the wearer may use the garment shield of this invention without being aware that she is wearing the garment shield. Further, the disposable feature means that the garment shield need not be washed and re-used which has obvious sanitary as well as labor saving advantages.

Although the device of this invention has been described in detail above it is not intended that the invention should be limited by this description but only in accordance with the spirit and scope of the appended claims in which I claim:

1. A blank for a garment shield having multiple layers of material in sequence comprising: a first layer of nylon gauze having a bias thread in a first direction, a second layer of nylon gauze having a bias thread in a second direction, a third layer of moisture absorbing material, a fourth layer of very thin polyethylene, a fifth layer of nylon gauze having a bias thread in one direction, and a sixth layer of nylon gauze having a bias thread in a direction different than said last named layer of nylon gauze.

2. In combination: an oval shaped garment shield blank having a plurality of layers of material in sequence, a first said layer being of nylon gauze with one thread direction substantially in the direction of the minor axis of said oval and the second thread direction on a bias with the major axis of said oval forming a bias angle with a first direction, a second layer of nylon gauze having one thread direction parallel to the minor axis of said oval and second thread direction on a bias with the major axis of said oval the bias angle of said second layer being opposite in direction to that of the bias angle of said first layer, a third layer of moisture absorbing cellulose material, a fourth layer of thin polyethylene, a fifth layer of nylon gauze having one thread direction parallel to the minor axis of said oval and the second thread direction on a bias with the major axis of said oval, and a last layer of nylon gauze having one thread direction substantially parallel to the minor axis of said oval and a second thread direction on a bias with the major axis of said oval the bias angle of said last named layer being opposite in direction from that of the bias angle of said fifth layer, said layers being heat fused on the periphery thereof.

3. A garment shield blank as claimed in claim 2 and further comprising: adhesive material attached to the periphery of the exterior side of said last named layer.

4. A disposable garment shield comprising: a substantially oval shaped blank of multilayered material heat-fused together on the periphery of said oval and folded substantially along the minor axis of said oval; a second fold indented into said first fold to form a substantially crescent shaped indentation, said indentation extending over substantially the center two-thirds of said fold to cause said fold to be depressed in the region of said indentation; and positioning marks positioned on the outer surface of said blank on at least one line parallel to the major axis of said oval said last named line positioned approximately one-third of the distance across said minor axis; the layers of said blank being in sequence a first layer of nylon gauze having one thread direction substantially parallel to the minor axis of said oval and a second thread direction forming a bias angle in a first sense with the major axis of said oval, a second layer of nylon gauze having a first thread direction forming a bias angle in a sense opposite to said first sense with the major axis of said oval, a third layer of moisture absorbent fibrous material, a fourth layer of very thin polyethylene, a fifth layer of nylon gauze having one direction substantially parallel to the minor axis of said oval and a second thread direction forming a bias angle in a third sense with the major axis of said oval, a sixth layer of nylon gauze having one thread direction substantially parallel to the minor axis of said oval and a second thread direction forming a bias angle in a sense opposite to said third sense with the major axis of said oval.

5. A garment shield as recited in claim 4 and further comprising adhesive material positioned on the exterior surface of the periphery of said garment shield.

6. A blank for a garment shield having multiple layers of material in sequence comprising: a first layer of porous fabric having a bias thread in a first direction, a second layer of porous fabric having a bias thread in a second direction, a third layer of moisture absorbing material, a fourth layer of very thin polyethylene, a fifth layer of porous fabric having a bias thread in one direction, and a sixth layer of porous fabric having a bias thread in a direction different than said last named layer of porous fabric.

7. In combination: an oval shaped garment shield blank having a plurality of layers of material in sequence, a first said layer being of porous fabric with one thread direction substantially in the direction of the minor axis of said oval and the second thread direction on a bias with the major axis of said oval forming a bias angle with a first direction, a second layer of porous fabric having one thread direction parallel to the minor axis of said oval and the second thread direction on a bias with the major axis of said oval the bias angle of said second layer being opposite in direction to that of the bias angle of said first layer, a third layer of moisture absorbing cellulose material, a fourth layer of thin polyethylene, a fifth layer of porous fabric having one thread direction parallel to the minor axis of said oval and the second thread direction on a bias with the major axis of said oval, and a last layer of porous fabric having one thread direction substantially parallel to the minor axis of said oval and a second thread direction on a bias with the major axis of said oval the bias angle of said last named layer being opposite in direction from that of the bias angle of said fifth layer, said layers being heat-fused on the periphery thereof.

8. A garment shield blank as recited in claim 7 and further comprising: adhesive material attached to the periphery of the exterior side of said last named layer.

9. A disposable garment shield comprising: a substantially oval shaped blank of multilayered material heat-fused together on the periphery of said oval and folded substantially along the minor axis of said oval; a second fold indented into said first fold to form a substantially

crescent shaped indentation, said indentation extending over substantially the center two-thirds of said fold to cause said fold to be depressed in the region of said indentation; and positioning marks positioned on the outer surface of said blank on at least one line parallel to the major axis of said oval said last named line positioned approximately one-third of the distance across said minor axis; the layers of said blank being in sequence a first layer of porous fabric having one thread direction substantially parallel to the minor axis of said oval and a second thread direction forming a bias angle in the first sense with the major axis of said oval, a second layer of porous fabric having a first thread direction forming a bias angle in a sense opposite to said first sense with the major axis of said oval, a third layer of moisture absorbent fibrous material, a fourth layer of very thin polyethylene, a fifth layer of porous fabric having one direction substantially parallel to the minor axis of said oval and a second thread direction forming a bias angle in a third sense with the major axis of said oval, a sixth layer of porous fabric having one thread direction substantially parallel to the minor axis of said oval and a second thread direction forming a bias angle in a sense opposite to said third sense with the major axis of said oval.

10. A garment shield as recited in claim 9 and further comprising adhesive material positioned on the exterior surface of the periphery of said garment shield.
